UNITED STATES PATENT OFFICE.

HERBERT A. DURR, OF CHICAGO, ILLINOIS.

APPARATUS FOR STEAM-HEATING.

1,229,917.

Specification of Letters Patent. Patented June 12, 1917.

Application filed July 5, 1916. Serial No. 107,574.

To all whom it may concern:

Be it known that I, HERBERT A. DURR, a citizen of the United States, residing at Chicago, county of Cook, and State of Illinois, have invented certain new and useful Improvements in Apparatus for Steam-Heating, of which the following is a specification.

The present invention has to do with a new and improved system of heating, and certain apparatus to be used in connection with the same.

The system of steam heating, as generally practised, is open to the objection that it does not present flexibility of control. That is to say, it is open to the objection that the temperature of the radiators and the amount of heat radiation cannot be readily controlled according to the necessities presented by the weather, etc. This is because the steam in the radiators must of necessity be at a comparatively high temperature, and generally somewhat above 212° Fahrenheit. Otherwise there will be no steam present and consequently no transmission of heating medium from the boiler to the radiators.

This deficiency in the principle of steam heating is well understood and accepted in the art and in the past certain attempts have been made to overcome the same by control of the amount of radiating surface to which the steam is applied. Such control, for example has been attempted by the use of the so-called vapor heating system, in which the air entrapped in the radiators is so regulated as to prevent the admission of steam to the entire body or volume of the radiator. This principle and application are, however, open to the very serious objection that the air within the radiator is a compressible medium, so that the volume or space within the radiator which will be occupied by the steam will depend in large measure upon the pressure of the steam and the consequent compression of the air. It is also open to the objection that it is a two-pipe system.

I have discovered the fact that by substituting in place of the air a non-compressible medium such as water or the like, the volume or space within the radiator available for the accommodation of the steam may be very nicely and accurately controlled, so that the radiating effect of the radiator may be controlled and maintained at a given

desired point and without fluctuation or variation on account of change in the steam pressure. This makes it unnecessary in the practice of my invention to provide accurate, 60 and in most cases, delicate pressure regulating mechanism, and the system of steam heating, according to my invention, will operate accurately and exactly, as desired at all times with a given setting of the control mechanism.

On account of the fact that the water of condensation from the steam itself is, to all practical intents and purposes, non-compressible, I find that this constitutes a simple and desirable medium for the regulation of the space or volume within a radiator available for the accommodation of the steam. When using the water of condensation in this manner a simple method consists in the entraining of water of condensation within the radiator until a desired volume or portion of the radiator is thereby filled or occupied. Thereafter, the radiation may be maintained at a constant point 80 by maintaining only the desired amount of condensation within the radiator, permitting the additional condensation to discharge from time to time, or continuously, as desired.

In the drawing:

Figure 1 shows one arrangement for the practice of the features of my invention;

Fig. 2 shows a vertical elevation, partly in section, of a valve mechanism by means 90 of which the features of the present invention may be carried into effect by the use of the water of condensation, the regulation of radiating surface being accomplished by regulating the amount of condensation contained in the radiator;

Fig. 3 shows a section taken on the line 3-3 of Fig. 2, looking in the direction of the arrows, said section being on enlarged scale; and

Fig. 4 shows a section taken on the line 4-4 of Fig. 2, looking in the direction of the arrows, Fig. 4 also being on enlarged scale.

I will first describe the particular steam layout illustrated in Fig. 1 for practising the features of the present invention. In the particular arrangement illustrated the boiler 5 supplies steam through the connection 6 and valve 7 to a steam loop 8. This steam loop is pitched from the point 9 downwardly to the point 10 in accordance with estab-

lished practice, so that condensation drains toward the end 10. The radiators are tapped off from the steam loop at desired points, the condensation from each radiator returning around the loop to the point 10.

In the particular arrangement illustrated, I have shown two radiators numbered 11 and 12, respectively, connected into the loop at opposite sides thereof.

10 The condensation returning to the end 10 is delivered to a balance tank 13, and the water is supplied from said balance tank to the boiler by a connection 14. The elevation of water within the balance tank serves to 15 control the supply of water thereto. A water supply line 15 delivers water to the balance tank, and a discharge connection 16 serves to overflow water to a sump or sewer in accordance with established practice. 20 Control valves, such as float valves or the like 17 and 18, serve to regulate the supply and discharge of water to and from the balance tank, so that at all times the level therein will remain within desired limits. 25 These float valves may be of any suitable construction and I will not further describe them in detail. It will be understood, however, that the balance tank 13 with the supply line 15, and discharge connection 16 30 in conjunction with the valves 17 and 18 are shown simply as a convenient means for regulating the level of water within the tank when it is desired to secure such result.

Reference to Figs. 2, 3 and 4 will show 35 in detail the construction of the valve herein illustrated for the purpose of regulating the amount of condensation entrained in the radiator. A well known and standard form of radiator coil is provided with upper 40 and lower taps which are located adjacent to the upper and lower extremities of the coil.

The valve shown in detail in the drawings includes the upper and lower heads 19 and 45 20, respectively, and the intermediate tubular connecting section 21. These upper and lower heads are provided with nipples 22 and 23 for connection into the upper and lower portions of the radiator, as by means 50 of the taps heretofore referred to.

The elevation of water within the tubular section 21 will be equal to the elevation of the condensation within the radiator. Therefore, the tubular section 21 presents a convenient mechanism whereby to regulate the elevation of the condensation. In the particular construction illustrated, a stationary web 24 is formed in the lower head 20. The said stationary web is provided with an 55 elongated steam slot 25 and with a condensation discharge orifice 26, as shown in Fig. 4. A plate 27 is rotatably mounted on the upper surface of the web 24, and said plate may be rotated through the medium of a 60 rod 28 which extends upwardly through a 65

guide web 29, and packing 30 to the handle 31. By rotating the handle the plate 27 will be rotated on the upper surface of the web 24.

The plate 27 carries an upstanding steam 70 tube 32, the elevation of which is equal to or greater than the greatest height to which the condensation will be required to stand within the radiator. The plate 27 is also provided with a number of other tubes 33, 75 34, 35 and 36, of different elevations corresponding to the different levels at which it may be desired to maintain the condensation within the radiator.

In the particular construction illustrated 80 the tube 33 stands substantially at three-quarters elevation, the tube 34 substantially at one-half elevation, the tube 35 substantially at one-quarter elevation, and the tube 36 is substantially nothing but a discharge 85 hole or orifice.

With the plate 27 turned into the position shown in Fig. 3 with respect to the web 24, it will be observed that both of the openings 25 and 26 will be entirely closed or shut off. 90 Consequently, steam cannot enter the radiator, nor can water of condensation discharge therefrom. In other words the valve is entirely closed. By turning the valve a suitable amount to carry the steam pipe 32 into 95 communication with the opening 25, the water discharge pipe 33 will be brought into communication with the port or opening 26. Now, the pipe 33 stands three-quarters high with respect to the radiator. Consequently, 100 with the valve in this position the steam will deliver into the radiator and will condense therein, and this action will continue until the radiator has become three-quarters filled with water of condensation. Thereafter, 105 any further condensation will overflow the pipe 33 and discharge back to the steam line and find its way to the balance tank.

In other words, with the valve in this position, three-quarters of the volume of the 110 radiator will be filled with water of condensation and only one-quarter of the volume of the radiator will be available for live steam. Consequently, the effective radiating area of the radiator will be cut down 115 to practically one-fourth of the full area of the radiator. By turning the valve to the next position, the pipe 33 will be brought into communication with the opening 25 in addition to the pipe 32, and the pipe 34 will 120 be brought into communication with the discharge port 26. This will permit water of condensation to drain out of the radiator down to the level of the upper end of the pipe 34, so that the radiator will be there- 125 after only half full of water of condensation.

This will greatly increase the effective radiating capacity. In like manner, by turning the valve an additional amount, the pipe 130

34 will be transferred into communication with the opening 25 and the pipe 35 will be brought into communication with the port 26, so as to permit the radiator to remain only one-fourth filled with water of condensation. Finally, by turning the valve an additional amount, the pipe 35 will be placed into communication with the opening 25, and the pipe or opening 36 will be brought into communication with the port 26. This will cause the radiator to drain substantially free of condensation, thus giving the maximum radiating capacity.

Of course, if the valve be opened, the full extent in the first instance, or to any position intermediate between the maximum and minimum openings, the water of condensation will rise within the radiator to the point where it will overflow that pipe which is in communication with the discharge port.

It will be observed that as the valve is turned more and more in the direction of a full opening, more and more of the pipes are brought directly into communication with the opening 25. Simultaneously, the elevation of the water of condensation is reduced or conversely the amount of effective radiating surface is increased. This means that there will be an additional demand for steam, but said additional demand may be readily satisfied because of the additional pipe area presented for the delivery of steam into the radiator on account of the bringing of additional pipes into communication with the opening 25.

A spring 39, having its lower end in engagement with a collar 40, on the rod 28, serves to maintain the valve plate 27 at all times in firm contact with the valve seat 24. The amount of condensation, as the control valves of the different radiators on the system are opened and closed to a greater or less extent, will increase or decrease. This will cause at times a heavy demand for steam from the boiler, and a comparatively rapid return of water to the balance tank. It is intended by the use of the valves 17 and 18 in the balance tank to regulate therein the water level. In case of an extremely

heavy demand for steam, the balance tank will supply water through the pipe 14 to the boiler, whereupon the float 17 will fall, thus permitting the supply of water through the line 15 to the balance tank and thence through the pipe 14 to the boiler.

In case there is a return of water of condensation from the radiators at a rate greater than the rate of evaporation of steam, the level of the water within the balance tank will rise, thus raising the float 18 and permitting a discharge of water through the pipe 16.

It is, however, very desirable to maintain the level of the water constant within the boiler itself, and in many cases where there

is a heavy return of water from the radiators, the said water would not discharge through the pipe 16 at a sufficient rate to prevent an abnormal rise of water level in the boiler.

I have, therefore, shown a float valve 37 interposed in the pipe 14. This float valve includes a chamber 38 within which a sufficient amount of water will be carried to properly operate the float 37. The level of the water within the chamber 38 will be equal to the level within the boiler. Consequently, when the water within the boiler stands at the desired level, the float 37 will close the pipe 14 so as to prevent, for the time being, a further delivery of water from the balance tank to the boiler. When the water level falls within the boiler, the float 37 will fall so as to permit the delivery of water to the boiler until the level within the boiler has been restored to the desired point.

It is evident that by the use of the mechanisms herein disclosed there is provided a considerable storage capacity within the balance tank, so as to take up normal fluctuations of water of condensation, and it is also evident that means have been provided for preventing a flooding of the boiler in case of an abnormal return of water of condensation.

It will be observed that by the use of the system herein disclosed, it is possible to control the effective radiating capacity of the radiator with the use of a one-pipe system. This is a very great advantage over the so-called vapor system to which reference has previously been made, because the so-called vapor system necessitates the use of two pipes on each radiator, and corresponding additional pipes throughout the entire system.

While I have herein shown and described only a single application of my improved system and only a single form of mechanism for carrying the said system into effect, still it will be understood that I do not limit myself to the same, except as I may do so in the claims.

I claim:

1. The combination with a radiator and a single pipe for the delivery of steam and removal of water of condensation to and from the radiator, of a valve mechanism interposed between said pipe and said radiator, said valve mechanism comprising upper and lower connections in communication with the interior of the radiator, a tubular member joining the interior portions of said connections, a horizontal partition in the lower connection, there being an arcuate slotted opening in said partition, another opening in said partition adjacent to one end of said arcuate slotted opening, a disk rotatably mounted on the upper surface of said partition, said disk having a plurality

of perforations extending through its body, said perforations being located in arcuate position corresponding to the afore-mentioned arcuate slotted opening, a steam tube 5 upstanding from the end one of said openings, and a series of condensation tubes upstanding from selected ones of the other openings, said condensation tubes being of selectively decreasing elevation commencing 10 with the condensation tube next in order to the steam tube, and means for rotating the disk with respect to the partition, substantially as described.

2. The combination with a radiator and a 15 single pipe for the delivery of steam and removal of water of condensation to and from the radiator, of a valve mechanism interposed between the pipe and the radiator, said valve mechanism comprising an 20 elongated valve member having its upper and lower ends in communication respectively with the upper and lower portions of the radiator, a horizontal partition in the lower portion of the valve mechanism, there 25 being an arcuate slotted opening in said partition, a disk rotatably mounted on the upper surface of the partition, there being a plurality of openings extending through said disk, said openings lying in arcuate 30 fashion corresponding to the arcuate slotted opening, a steam pipe upstanding from the end one of said disk openings, condensation pipes upstanding from selected ones of the other disk openings, the condensation pipes 35 being of selectively decreasing elevation commencing with the condensation pipe next adjacent to the steam pipe, and means for turning the disk into selected positions, substantially as described.

40 3. The combination with a radiator and a single pipe for the delivery of steam and the removal of water of condensation to and from the radiator, of a valve device interposed between the pipe and the radiator, 45 said valve device comprising an elongated member having its upper and lower ends in

communication with the upper and lower portions of the radiator, a horizontal partition in the lower portion of the valve device, there being an elongated opening extending 50 through said partition, a disk movably mounted on the upper surface of the partition, there being a plurality of openings extending through said disk, a plurality of pipes upstanding from the openings of the 55 disk, the end one of said pipes being a steam pipe, and the other pipes, being of progressively decreasing elevation, and being water pipes, and means for moving the disk over the surface of the partition to bring said 60 pipes successively into communication with the elongated opening, substantially as described.

4. The combination with a radiator and a single pipe for the delivery of steam and 65 the removal of water of condensation to and from the radiator, of a valve device between the pipe and the radiator, said valve device including an elongated vertical tubular member having its upper and lower ends in 70 communication with the upper and lower portions of the radiator, a partition in the lower portion of said valve device, there being an arcuate slotted opening in said partition, a disk rotatably mounted on the upper 75 surface of the partition, there being a plurality of openings extending through said disk and located in arcuate fashion corresponding to the arcuate slotted opening of the partition, a plurality of pipes connected 80 to the disk and upstanding from the aforesaid openings, the end pipe being a steam pipe of maximum height, and the other pipes being water pipes of progressively decreasing height, and means for rotating the 85 disk over the face of the partition, substantially as described.

HERBERT A. DURR.
